UNITED STATES PATENT OFFICE

LLOYD W. DICKINSON, OF STONE LAKE, WISCONSIN, ASSIGNOR OF ONE-HALF TO MERTON K. ARFORD, OF STONE LAKE, WISCONSIN

COMBINED CIGARETTE EXTINGUISHER AND ASH RECEPTACLE

Application filed January 12, 1932. Serial No. 586,206.

My invention relates to a combined cigarette extinguisher and ash receptacle.

An important object of the invention is to provide a device of the above-mentioned character, having a tubular element for receiving ashes, and cigarettes, with means to squeeze lit cigarettes to extinguish the same, preventing the objectionable burning of discarded cigarettes.

10 A further object of the invention is to provide a device of the above-mentioned character, which may be used alone or in conjunction with an ash tray.

15 A further object of the invention is to provide a device of the above-mentioned character, which is simple in construction, cheap to manufacture, and convenient in use.

20 In the accompanying drawing, forming a part of this specification, and in which like numerals are employed to designate like parts throughout the same,

Figure 1 is a side elevation of the device embodying my invention,

25 Figure 2 is a similar view taken at a right angle to Figure 1,

Figure 3 is a plan view of the device,

Figure 4 is a horizontal section taken on line 4-4 of Figure 1,

30 Figure 5 is a perspective view of the same,

Figure 6 is a vertical section taken on line 6-6 of Figure 3.

In the drawing, wherein for the purpose 35 of illustration, is shown a preferred embodiment of my invention, a vertical frame is shown embodying spaced vertical legs 7, rigidly held within eyes 8, formed at the ends of arms 9, included in an upper horizontal spider frame element. Each arm includes a pair of outwardly converging spaced sides 10, as shown.

40 Arranged inwardly of the inner ends of the arms 9, and rigidly attached thereto by any suitable means, as by welding or soldering, is a receiving tube 11, which is preferably tapered, and decreasing in diameter, downwardly. This tube is vertically arranged and projects below the spider frame 45 element.

Arranged beneath and adjacent to the lower reduced end of the tube 11, is a stationary blade or strip 12, the free ends of which are bent laterally for affording extensions 13, which, in turn, are bent into 55 eyes 14, receiving a pair of the legs 7, and rigidly clamped to these legs. Disposed upon the inner side of the stationary strip or blade 12 is a movable strip or blade 15, having a knuckle 16, at one end, receiving a 60 pintle 17, projecting beyond the ends of the knuckle and engaging over the edges of the stationary blade 12, and clamped thereto. The blade 15 is, therefore, pivoted at one end to the stationary blade, to swing 65 with relation thereto. The blade 15 is provided at its free end with an angular extension 18, to be conveniently engaged by the thumb or finger. The pivoted blade is further provided with a longitudinal reinforcing flange 19, apertured for engagement with a retractile coil spring 20, the opposite end of which is attached to one of the legs 7, adjacent to the eye 14. The spring 20 serves to swing the blade 15 outwardly, and this 70 outward movement is limited by a stop 21, attached to one leg 7.

75 Operating in conjunction with the blades 12 and 15 is a vertically swinging gate or valve 22, arranged beneath these blades in 80 close relation thereto. The gate 22 is adapted to swing vertically, and is provided at its outer end with a knuckle 23, receiving a 85 pintle 24, the ends of which are bent about and clamped to the edges of the horizontal supporting strip 25, which is rigidly attached to the blade 12, by any suitable means, and may also be rigidly attached to the oppositely arranged leg 7. The supporting strip is horizontally arranged, as shown. 90 The gate 22 is swung upwardly by a retractile coil spring 26, the lower end of which is attached to an extension or ear 27, carried by the gate 22 and the upper end of this spring is attached to the upper edge of the stationary blade 12. This spring normally holds the gate 22 in the upper horizontal position. This gate is swung downwardly 95 from this horizontal position by a vertical reciprocating rod 28, operating through a 100

stationary guide 29, and through an aperture 30, formed in the supporting strip 25, the lower end of the rod 28 resting upon the gate 22, at a point forwardly of its pivot, 5 but having no connection therewith. The rod 28 is moved upwardly by a retractile coil spring 31, attached thereto, and to one arm 9, as shown.

In the use of the device, the vertical 10 frame, as a whole, may be placed upon a larger tray or receptacle, while the invention is not restricted to this use. The device may be made in such a size that the tube 11 will hold a sufficient amount of ashes and 15 cigarettes, so that the same may be emptied at intervals. The gate 22 is normally in the upper horizontal position, and the stationary blade 12 is arranged adjacent to one side of the tube 11, while the movable blade 15 is 20 disposed adjacent to its opposite side. Ashes are introduced into the upper end of the tube 11, in the usual manner, and will flow through the same and accumulate upon the gate 22, between the blades 12 and 15, 25 and would pyramid thereon and close the lower end of the tube. It is, thus, seen that the entire tube might be filled with ashes before it is emptied, by depressing the rod 28 to swing the gate 22 downwardly. If it is 30 desired not to retain the ashes in the tube, the tube may be emptied at intervals, by depressing the rod 28. When a lit discarded cigarette is introduced into the tube, it will descend therein, and finally rest upon the 35 gate 22. This burnt cigarette is extinguished by squeezing the same between the blades 12 and 15, which is accomplished by swinging the blade 15 toward the blade 12. After the cigarette is extinguished, the blade 15 is 40 released, and will return to the open position, and the cigarette, with or without additional ashes, may be discharged from the space immediately beneath the tube 11, by depressing the rod 28.

45 It is to be understood that the form of my invention herewith shown and described is to be taken as the preferred example of the same, and that various changes in the shape, size, and arrangement of parts may be resorted to without departing from the spirit 50 of the invention, or the scope of the subjoined claims.

Having thus described my invention, what I claim is:

55 1. In a device of the character described, a support, a tube arranged thereon for receiving ashes and lit cigarettes, a movable gate arranged near and beneath the lower open end of the tube, and a pair of generally straight blades arranged between the gate and the lower open end of the tube, one blade being movable from an open position to a shut position in approximate contact with the other blade, so that a lit cigarette supported by the gate between the

blades may be squeezed by the blades and extinguished.

2. In a device of the character described, a support, a substantially vertical tube arranged thereon for receiving ashes and lit cigarettes or the like, a swinging gate arranged near and beneath the lower open end of the tube, and a pair of substantially horizontally arranged generally straight blades disposed between the gate and the lower end of the tube, one blade being adapted to be swung with relation to the other blade to assume a generally parallel close relation thereto so that a lit cigarette supported by the gate between the blades may be squeezed by the blades and extinguished. 75

3. In a device of the character described, a supporting frame, a substantially vertical tube arranged thereon for receiving ashes and lit cigarettes or the like, a vertically swinging gate arranged near and beneath the lower open end of the tube, a stationary substantially horizontal blade disposed between the gate and the lower end of the tube, a co-acting substantially horizontal blade 85 arranged between the tube and gate and hinged to the stationary blade for movement with relation thereto, and means to move the gate. 90

4. In a device of the character described, a supporting frame, a substantially vertical tube arranged thereon for receiving ashes and lit cigarettes or the like, a vertically swinging gate arranged near and beneath the lower open end of the tube, a stationary substantially horizontal blade disposed between the gate and the lower end of the tube, a co-acting substantially horizontal blade arranged between the tube and gate and hinged to the stationary blade for movement with relation thereto, a spring to swing the gate upwardly in close relation to the blades, a reciprocatory rod to engage the gate for opening the same and extending to the top of the tube, and a spring for 100 swinging the movable blade to the open position. 105

5. A combined cigarette extinguisher and ash receptacle, comprising a support, a tube arranged thereon for receiving ashes and lit cigarettes, a movable gate arranged near and beneath the lower end of the tube for normally supporting the contents of the tube, and means arranged near the lower end of the tube and above the gate for squeezing 115 the lit cigarettes and extinguishing the same. 120

In testimony whereof, I affix my signature.

LLOYD W. DICKINSON.
